CLAIM

The ornamental design for a gate as shown and described.

DESCRIPTION

FIG. 1 is a perspective view of a gate showing my new design;

FIG. 2 is the front view of the gate of FIG. 1;

FIG. 3 is aback view of the gate of FIG. 1;

FIG. 4 is a side view of the gate of FIG. 1;

FIG. 5 is the other side view of the gate of FIG. 1;

FIG. 6 is a top view of the gate of FIG. 1; and,

FIG. 7 is bottom view of the gate of FIG. 1.

The broken lines in the drawings depicting the gate handle, lock and wood inserts are portions of the gate that form no part of the claimed design.
